(57) **CLAIM**

The ornamental design for pair of footwear articles, as shown and described.

DESCRIPTION

FIG. 1 is a front perspective view of one article of a pair of footwear articles, showing my new design; FIG. 2 is a front view of the pair of footwear articles of FIG. 1;

FIG. 3 is a rear view of the pair of footwear articles of FIG. 1; FIG. 4 is a lateral side view of the pair of footwear articles of FIG. 1;

FIG. 5 is a medial side view of the pair of footwear articles of FIG. 1;

FIG. 6 is a top plan view of the pair of footwear articles of FIG. 1;

FIG. 7 is a bottom plan view of the pair of footwear articles of FIG. 1; and,

FIG. 8 is an alternative bottom plan view of the pair of footwear articles of FIG. 1.

The drawings show the design of an pair of footwear articles suitable for being worn on a left foot. The ornamental design also includes the mirror images of drawings, i.e., the design of an article of footwear suitable for being worn on the right foot. Broken (dashed) lines are for illustration purposes only and form no part of the claimed design.
